TROUSER LEG RAIN PROTECTOR

Eugene W. Ballenger, Brooklyn, N. Y.

Application December 29, 1943, Serial No. 516,055

1 Claim. (Cl. 36—2)

1

This invention relates to rain or weather protective garments, and aims to provide covering members which can be readily donned over the lower trousers legs and securely held in position, to protect the same from rain or snow. The desirability of such articles is indicated by the insufficiency of raincoats, as, although such coats protect the wearer from about the knees up to the neck, they offer no protection to the legs below the knees. This invention aims to overcome 10 that deficiency.

Another object of the invention is the provision of auxiliary protective means adapted to be readily attached or removed, in association with the trouser leg protectors, for further protecting the feet or shoes from the weather.

A further object of the invention is the provision of the above protectors in such manner that they may be quickly applied or removed, that they may be conveniently carried in the pocket of a raincoat, for instance, and that they may be manufactured inexpensively.

The above and other objects will become apparent in the description below, wherein characters of reference refer to like-numbered parts in the accompanying drawing. It is to be noted that the drawing is intended to serve the purpose of illustration only, and it is neither intended nor desired to limit the invention necessarily to the details of construction shown excepting insofar as they may be essential to the invention.

Referring briefly to the drawings,

Fig. 1 is a perspective view illustrating the wearing of the leg protectors.

Fig. 2 is a side elevational view showing one of the protectors being worn.

Fig. 3 is a cross-sectional view taken on the line 3—3 of Fig. 2.

Fig. 4 is a perspective view of one of the leg protectors.

Fig. 5 is an enlarged side view showing a shoe protector attached to one of the leg protectors.

Fig. 6 is a plan view of a shoe protector.

Fig. 7 is a cross-sectional view taken on the line 7—7 of Fig. 5.

Referring in detail to the drawing, the numeral 10 indicates the trouser leg rain protectors, which are made of any suitable material, preferably of a waterproof or water repellent type, and are shaped in the usual manner of trousers legs. They may be pressed into shape in the manner of trousers so as to present a neat appearance. At two points 11 at the front and back of the protector 10, flaps or loops 12 are secured to the top of the protector, to which adjustable straps or the

2

like 13 are attached, the latter being provided with any suitable type of connector or hook 14 to be slipped under the belt loops 15 of the wearer's trousers.

That these protectors may be quickly put on, with the hooks 14 looped under the belt loops 15, is obvious. When worn, they securely protect the lower trousers legs from the rain, as is seen in Fig. 1.

As a further improvement in the rain protectors, shoe protectors 16 may be provided, comprising a member formed in the shape of a flattened funnel, shown at 17, with the forward portion thereof elongated, as shown at 18. When worn in place, the member 16 covers the space between the protector 10 and the shoe, as well as all of the open or laced portion of the shoe.

The member 16 is formed of two layers of material, 19 and 20, doubled up from below, with a layer of stiff or shape-retaining yet pliable material 21, such as, for instance, buckram, therebetween. This layer is sewed in between the covering layers 19 and 20, and is shaped into the oval funnel-shaped member shown, either before being sewn in or after, and it thereby retains that shape for the entire shoe protector. A collar or flange 22 is provided along the upper periphery of the shoe protector 16, on which a plurality of halves of snap buttons 23 are provided, the cooperating or complementary halves of these buttons being provided along the lower edge of the leg protector 10. The collar 22 registers inside the protector 10, and when so worn it is obvious that rain will be kept off the socks of the wearer between the shoes and the trousers and also through the shoe lace openings of the shoe.

It is apparent from the above that a practical and simple rain protector has been provided which fills the needs of a person wearing a raincoat, to protect his legs and feet fully from being soaked by the falling rain.

Obviously, modifications in form and structure may be made without departing from the spirit and scope of the invention.

45 I claim:

A rain protector comprising a leg member simulating approximately the lower half of a trousers leg, a pair of adjustable straps secured at their lower ends to opposed points of the upper edge 50 of said leg member, said straps having hooks at their upper ends adapted to engage the trouser belt loops of the wearer, a substantially funnel-shaped member adapted to be worn on the upper portion of the shoe of the wearer, the forward and rearward portions of said funnel-shaped

member being elongated, said member having a similarly shaped shape-retaining material secured around the entire periphery thereof and having a collar extension on the upper periphery thereof registering inside said leg member, and snap button fastening means partly on said leg member and partly on said collar for detachably securing said collar to said leg member
